CLAIM

I claim the ornamental design for an earring, as shown and described.

DESCRIPTION

FIG. 1 is a front, top, and right side perspective view of an earring, showing my new design;

FIG. 2 is a rear, bottom, and left side perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a right side elevational view thereof; and,

FIG. 8 is a left side elevational view thereof.

The dot-dashed lines denote the boundary of the claim, and form no part of the claimed design.
